[57] CLAIM

The ornamental design for combined wrist watch and strap, as shown and described.

DESCRIPTION

FIG. 1 is a top left front perspective view of a combined wrist watch and strap, showing my new design;

FIG. 2 is a top plan view;

FIG. 3 is a bottom plan view;

FIG. 4 is a left side elevational view;

FIG. 5 is a right side elevational view;

FIG. 6 is a front elevational view, with the strap not shown for ease of illustration;

FIG. 7 is a rear elevational view, with the strap not shown for ease of illustration;

FIG. 8 is an enlarged fragmentary top plan view of the stitching on the strap, shown for ease of illustration, and FIG. 9 is a rear elevational view of the strap buckle, the watch body not shown for ease of illustration.
